10 Claims

ABSTRACT OF THE DISCLOSURE

Compounds of the formula

in which R, R₁ and R₂ represent aliphatic residues, R₃ represents an alkyl group which may be linked with the phosphorus atom through oxygen or sulfur, X is O or S and Hal represents a halogen atom. The phosphoric acid ester amides are effective as selective herbicides as well as plant-growth regulators in useful plant crops.

Phosphoric and thiophosphoric acid ester amides are disclosed in the works of E. H. Blair et al. [J. Agr., Food Chemistry, volume 14, No. 3, page 299 (1966)]. During their investigations of the insecticidal action of these amides, it was found that they are phytotoxic.

The present invention is based on the observation that phosphoric and thiophosphoric acid ester amides of the general formula

in which the substituents R, independently of one another, represent hydrogen, an alkyl group having 1 to 4 carbon atoms or possibly R₁; R₁ represents an alkyl group having 1 to 4 carbon atoms, R₂ represents an alkyl or alkenyl group having 1 to 6 carbon atoms, R₃ represents an alkyl group having 1 to 5 carbon atoms which may be linked with the phosphorus atom through oxygen or sulphur, X represents an oxygen or a sulphur atom and Hal represents a halogen atom, having a pronounced selective activity against monocotyledonous weeds for example Panicum, Poa, Digitaria or Alopecurus, while leaving important (including monocotyledonous) useful cultures for example grain crops, rice, maize, turnips, flax, soybeans, cabbages and others, and in the case of some cultures, they even display a useful growth-regulating effect. Compounds that are especially active, are those in which the substituents R, independently of one another, represent hydrogen or an alkyl group having 1 to 4 carbon atoms.

This considerable breadth of activity was unexpected, and has not hitherto been known to a similar extent with phosphorus compounds.

The weeds can be combated in the plant cultures both by the pre-emergent and the postemergent treatment, though the pre-emergent treatment is preferred.

2

In addition, the compounds of the Formula I display a good fungicidal activity when applied in small quantities.

Compounds of the formula

have a mainly selective herbicidal activity; in this formula the substituents R, independently of one another, represent hydrogen or an alkyl group having 1 to 4 carbon atoms, R₃ represents an alkyl group having 1 to 5 carbon atoms, which may be linked with the phosphorus atom through oxygen or sulphur, X represents an oxygen or a sulphur atom, and Hal is a halogen atom.

Among the said compounds, there are especially suitable for this purpose those which correspond to the formula

in which the generally indicated substituents R₁, R₃, Hal and X have the above meanings.

30 A group of compounds of importance to the selective control of plants comprises the compounds of the formula

in which R' represents a hydrogen atom or the methyl group, R represents a hydrogen atom or an alkyl group having 1 to 4 carbon atoms, R₃ represents an alkyl group and Hal represents a halogen atom.

45 The compounds of the general Formula I are new. They can be manufactured by various methods:

(a) A suitable phenol is reacted with phosphorus trichloride and sulphur, and the resulting

50 is reacted successively with (A) a suitable lower alkanol or lower alkanethiol and (B) a lower alkylamine, in either order, and dehydrohalogenation is repeated twice. In an identical manner, phosphorus tribromide may be used as starting material.

55 When, instead of a phosphorus trihalide, a phosphorus oxyhalide without addition of sulphur is used, the resulting

60 can be used in the further reaction.

(b) Alternatively, in a different sequence of operations O-alkyl-dichlorophosphate or -dichlorothiophosphate, or

3

alkyldichloro-dithiophosphate may be used as starting material and reacted with the corresponding phenol and then with the desired alkylamine.

(c) Alternatively, the parent phosphorus component (PCl_3 , PBr_3 or PXCl_3) may be reacted first with the alkyl-amine and the resulting

with the lower alkanol or mercaptan and the phenol, in either order of sequence.

As mild dehydrohalogenating agents, which may advantageously be added, there may be used: anhydrous hydrogencarbonates or carbonates, also tertiary amines for example triethylamine, pyridine, picoline, lutidine, quinaldine, diethylvanilene and dimethylvanilene.

In general, the new compounds of the general Formula I are used alone or in conjunction with additives in the form of herbicidal preparations.

The present invention also provides a selective herbicidal preparation which comprises a compound of the general Formula I given above together with a suitable carrier.

As additives for use in plant control, the known herbicides whose activity supplements that of the compounds of this invention may be employed, for example 2-methyl-4-chlorophenoxyacetic acid, 2-methyl-4-chlorophenoxybutyric acid and/or α -[2-methyl-4-chlorophenoxy]-propionic acid, and growth hormones.

The preparations may also contain one or more of the following: a vehicle, a solvent, a diluent, a dispersant, an emulsifier, a thickener, an adhesive and/or a fertilizer and, if desired, further pesticidal agents from the same or other spheres of application.

The form in which these preparations are applied depends entirely on their future use. They can be applied in a wide variety of forms, for example in the form of emulsions, dusting powders, dispersions or granulates.

Ready spray solutions of the compounds of the general Formula I can be prepared, for example, with petroleum fractions of a high to medium boiling range, for example diesel oil or kerosene, coal tar oil and oils of vegetable or animal origin, also hydrocarbons for example alkylated naphthalenes, tetrahydronaphthalene, if desired with the use of xylene mixtures, cyclohexanols, ketones or chlorinated hydrocarbons for example trichlorethane or tetrachlorethane, trichlorethylene, or tri- or tetrachlorobenzenes. It is advantageous to use organic solvents having boiling point above 100° C.

Aqueous forms of application are advantageously prepared from emulsion concentrates, pastes or wettable spray powders by the addition of water thereto. Suitable emulsifiers or dispersants are nonionic products, for example condensation products of aliphatic alcohols, amines or carboxylic acids with a long-chain hydrocarbon residue having about 10 to 20 carbon atoms, with ethylene oxide, for example the condensation product of octadecyl alcohol with 25 to 30 mols of ethylene oxide, or of commercial oleylamine with 15 mols of ethylene oxide, or of dodecylmercaptan with 12 mols of ethylene oxide. As anionic emulsifiers that can be used, there may be mentioned the sodium salt of dodecyl alcohol-sulphuric acid ester, the sodium salt of dodecylbenzenesulphonic acid, the potassium or triethanolamine salt of oleic or abietic acid or of mixtures of these acids, or the sodium salt of a petroleum sulphonate acid. Suitable cationic dispersants are quaternary ammonium compounds, for example cetyl pyridinium bromide or dihydroxyethyl benzyl dodecyl ammonium chloride.

4

As solid vehicles used in the manufacture of dusting and casting preparations there may be used: talcum, kaolin, bentonite, calcium carbonate, or coal, cork meal, wood meal or other materials of vegetable origin. It is also very advantageous to manufacture the preparations in granular form, especially for treating rice cultures in water. The different forms of application may contain the usual additives that improve the distribution, adhesion, stability to rain or the penetration; such substances are fatty acids, resins, casein or alginates.

The following examples illustrate the invention, the parts being by weight, unless otherwise indicated.

EXAMPLE 1

- 15 36.5 parts of 2-bromo - 5 - tertiary butylphenylthiodi-
chlorophosphate [boiling at 118-120° C. under 0.2 mm.
Hg; prepared by reacting 2-bromo-5-tertiary-butylphenol
in the usual manner with phosphorus trichloride and sul-
phur] in 50 parts by volume of methylene chloride and
20 6.4 parts of methanol are boiled under reflux for 16 hours.
The readily volatile phase is evaporated under vacuum at
50° C. bath temperature, to leave 35 parts of O-methyl-2-
bromo-5-tertiary butylphenylthioclorophosphate.

25 34 parts of this compound are dissolved in 150 parts by
volume of methylenechloride and 11.2 parts of isopropyl-
amine are added drop by drop during 30 minutes at 15-
25° C. The batch is stirred overnight at room temperature,
100 parts of water are added and the organic layer is
30 separated, washed, washed successively with 30 parts of
water, 2×20 parts of dilute sodium hydroxide solution
and dried over sodium sulphate. After having removed
the solvents under vacuum at 50° C. bath temperature
there are obtained 33 parts of the compound of the for-
35 mula

- 45 as a thickly liquid oil. $n_D^{23}=1.5418$ [Compound No. 1].
In an analogous manner the following thiophosphoric acid ester amides of the formula

are obtained:

- 60

Compound No.	Hal	R's	R	Refractive index
2	Br	Methyl	Methyl	$n_{D}^{23} = 1.5516$
3	Br	do	Ethyl	$n_{D}^{23} = 1.5463$
4	Br	do	n-Propyl	$n_{D}^{23} = 1.5422$
5	Br	do	n-Butyl	$n_{D}^{23} = 1.5372$
6	Br	Ethyl	Isopropyl	$n_{D}^{23} = 1.5335$
7	Br	do	Ethyl	$n_{D}^{23} = 1.5462$
8	Br	Propyl	Methyl	$n_{D}^{23} = 1.5424$
9	Br	do	Isopropyl	$n_{D}^{23} = 1.5300$
10	Cl	Methyl	do	$n_{D}^{23} = 1.5320$
11	Cl	do	Methyl	$n_{D}^{23} = 1.5428$
12	Cl	do	Ethyl	$n_{D}^{23} = 1.5424$
13	Cl	do	n-Propyl	$n_{D}^{23} = 1.5337$
14	I	do	Methyl	$n_{D}^{23} = 1.5554$
15	I	do	Ethyl	$n_{D}^{23} = 1.5562$
16	I	do	n-Propyl	$n_{D}^{23} = 1.5440$
17	I	do	Isopropyl	$n_{D}^{23} = 1.5442$

as well as the following compounds:

Compound No.	Formula	Refractive index
18		$n_{D}^{25}=1.5368$
19		$n_{D}^{25}=1.5476$
20		$n_{D}^{25}=1.5458$
21		$n_{D}^{25}=1.5518$
22		$n_{D}^{22}=1.5470$

EXAMPLE 2

34.6 parts of 2-bromo-5-t-butylphenylidichloroprophosphate [boiling at 115° C. under 0.2 mm. Hg; prepared in the usual manner by reacting 2-bromo-5-tertiary butylphenol with phosphorus trichloride] in 200 parts by volume of carbon tetrachloride are reacted at 20 to 30° C. with 6 parts of ethanol, then the hydrochloric gas is expelled with nitrogen and the residue reacted with 16 parts of isopropylamine. Working up in the usual manner furnishes 30 parts of the compound of the formula

50 parts of active substance of this invention

45 20 parts of Hisil (highly adsorptive silica)

25 parts of bolus alba (kaolin)

3.5 parts of an adduct of para-tertiary octylphenol with ethylene oxide

1.5 parts of sodium-1-benzyl-2-stearylbenzimidazole-6,3'-disulphonate.

Emulsion concentrate.—Readily soluble active substances can also be formulated as emulsion concentrates in the following manner:

55 20 parts of active substance, 70 parts of xylene and 10 parts of a mixture of the reaction product of an alkylphenol and ethylene oxide with calcium dodecylbenzenesulphonate are mixed together. When this mixture is diluted with water to the desired concentration, an emulsion ready for spraying is obtained.

60 Granulate.—7.5 grams of one of the active substances of Formula I are dissolved in 100 cc. of acetone and the resulting acetonnic solution is poured over 92 g. of granulated attapulgite (mesh size: 24/48=apertures/inch). The whole is thoroughly mixed and the solvent extracted in a rotary evaporator, to furnish a granulate containing 7.5% of active substance.

EXAMPLE 3

In the preemergent treatment, the new active substances of the Formula I displayed an excellent activity against grass-like weeds, while leaving cultures of grain crops, rice and maize as well as of dicotyledenous plants unaffected.

The treatment was carried out with 5 and respectively 2.5 kg. of active substance per hectare on the day after seeding. Evaluation was carried out 20 days later. The

[Compound No. 23].

Examples of formulations

Dusting agent.—Equal parts of an active substance according to this invention and of precipitated silica are finely ground together. From this mixture, dusting preparations containing preferably 1 to 6% of active substance, can be manufactured by incorporation of kaolin or talcum.

Spray powder.—For manufacturing a spray powder, for example, the following ingredients are mixed and finely ground together:

In the preemergent treatment, the new active substances of the Formula I displayed an excellent activity against grass-like weeds, while leaving cultures of grain crops, rice and maize as well as of dicotyledenous plants unaffected.

The treatment was carried out with 5 and respectively 2.5 kg. of active substance per hectare on the day after seeding. Evaluation was carried out 20 days later. The

resulting values are shown in the following Table 1, in which

1-2=plant undamaged

3-4=temporary damage

5-7=major damage

8-9=development of plant totally inhibited or plant killed.

TABLE 1

Compound	5 kg active substance per hectare					2.5 kg active substance per hectare				
	1	2	3	17	10	1	2	3	4	17
Test plant:

EXAMPLE 4

Experiments in rice cultures
Earth mixed with seeds of the weed *Panicum crus galli* was introduced into vessels of asbestos cement (60 x 60 x 40 cm.) are covered with a 2 cm.-layer of water. The pre-swelled rice seed material, in one case of the Caloro type and in the other of the Hatsunisiki type, in admixture with the abovementioned granulate of one of the active substances was sprinkled into the water. The amount of active substance applied ranged from 1 to 6 kg. per hectare.

14 days after the application, the values shown in the following Table 2 were recorded (evaluation as in Example 3).

These experiments revealed the high specific selectivity of the compounds of this invention, which is observed even with as large amounts as 4 and 6 kg. respectively of the active substance per hectare. Thus, there is no damage to the rice plants, even if too much of the majority of the substances mentioned is accidentally applied locally.

TABLE 2

Compound No.	Kg. active substance per hectare	Type of rice			55
		Caloro	Hatsunisiki	Echinochloa	
2	1	1	1	8	55
	2	3	3	9

	2	1	1	6	

EXAMPLE 5

Growth regulation

The compounds of the general Formula I are capable of regulating plant growth, and with various plants they produce stunted growth by inhibiting the growth in height and the internodal growth respectively. The plants thus changed do not turn yellow, do not suffer any other damage and remain photosynthetically active. As a result of the treatment with the above-mentioned compounds, it is often observed that the leaves are darker green in colour. The said compounds, or preparations containing them, also have further growth regulating properties; among others, they cause increased formation of lateral shoots with various plants.

The following 10 plants were sown and 10 days after emergence were sprayed with 2.5 kg. of active substance per hectare; Beta, *Calendula chrysanthemum*, *Chrysanthemum segetum*, *Linum usitatissimum*, *Brassica rapa*, *Ipomoea purpurea*, *Gossypium hirsutum*, *Soja max.*, *Galium aparine*, and *Stellaria media*.

Evaluation was carried out after 20 days. The average growth inhibition evaluated for this representative selection of plants, for the individual active substance according to this invention was:

Compound No.	Scale No.	Compound No.	Scale No.
2	3.7	11	2.9
3	3.6	12	3.6
4	3.0	13	2.5
5	2.1	14	3.7
6	3.2	15	4.0
7	4.1	16	2.5
8	2.1	17	2.9
10	3.9		

The degree of growth inhibition is scaled from 1 to 5; 1=no inhibition to 5=strong growth inhibition.

(B) In the same manner as described under (A) above, the special growth inhibition of two important useful plant cultures (*Lin.*=*Linum usitatissimum*; *Goss.*=*Gossypium hirsutum*) was determined:

Compound No.	Lin.	Goss.	Compound No.	Lin.	Goss.
2	5	2	11	5	3
3	5	3	12	4	3
4	4	3	13	2	3
5	1	4	14	4	3
6	5	2	15	5	3
7	5	3	16	3	2
8	2	2	17	4	3
10	6	3			

(C) Various species of chrysanthemum plants, were seeded, and 7 weeks later their leaves were sprayed with a solution of 1000 parts per million of the active substance No. 3. When these plants blossomed out 7 weeks later, the height of their growth was distinctly reduced in comparison with corresponding untreated chrysanthemum plants. The following heights of growth were recorded.

Average height of the main shoots in percent (length of main shoots of corresponding, untreated plants=100%)

Percent
<i>Chrysanthemum segetum</i> ----- 41
<i>Chrysanthemum parthenium</i> ----- 47
<i>Chrysanthemum coronarium</i> ----- 71
<i>Chrysanthemum carinatum</i> ----- 79
<i>Chrysanthemum indicum</i> ----- 58

No phytotoxic properties were observed in any experiment, that is to say that all plants had a healthy appearance, dark green leaves and a good flower formation.

(D) Wheat seeds were caused to germinate in distilled water for about 42 hours in the dark. The wheat seedlings, which had a length from 1 to 1.5 cm., were then transferred to culture vessels filled with active substance solu-

tion and, respectively, distilled water (=controls) and exposed to light. The active solution contained 100 parts per million of the active substance in the formulated preparation No. 3 in distilled water.

After 4 days, the solution of the active substance was replaced by a nutrient solution containing the same quantity of active substance (100 parts per million of active substance No. 3), while in the control experiments the distilled water was replaced correspondingly by a nutrient solution which did not contain the active substance.

Measuring the height of growth of the wheat plants was carried out 10 days later. It was found that in the case of the plants treated with the active substance, the height of the second stalk internode was reduced on an average by 33.1% in comparison with the controls. The height of the stalk from its base to the second ligula in the case of the plants treated with the active substance was on an average reduced by 36.3% in comparison with the controls.

I claim:

1. Compounds of the formula

in which the substituents R, independently of one another, represent a hydrogen atom, allyl, chloroallyl or R₁; R₁ represents an alkyl group having 1 to 4 carbon atoms, R₂ represents an alkyl group having 1 to 6 carbon atoms, allyl or chloroallyl, R₃ represents an alkyl group having 1 to 5 carbon atoms which may be linked with the phosphorus atom through oxygen or sulphur, X represents a sulphur atom and Hal is a halogen atom.

2. Compounds as claimed in claim 1 of the formula

in which the substituents R, independently of one another, represent a hydrogen atom or R₁; R₁ represents an alkyl group having 1 to 4 carbon atoms, R₂ represents an alkyl group having 1 to 6 carbon atoms, R₃ represents an alkyl group having 1 to 5 carbon atoms which may be linked with the phosphorus atom through oxygen or sulphur, X represents a sulphur atom and Hal is a halogen atom.

3. Compounds as claimed in claim 1 of the formula

in which the substituents R, independently of one another, represent a hydrogen atom or an alkyl group having 1 to 4 carbon atoms, R₃ represents an alkyl group having 1 to 5 carbon atoms which may be linked with the phosphorus atom through oxygen or sulphur, X represents a sulphur atom and Hal is a halogen atom.

4. Compounds as claimed in claim 1 of the formula

in which R, R₃, Hal and X have the meanings given in claim 3.

5. Compounds as claimed in claim 1 of the formula

in which R' represents a hydrogen atom or the methyl group, R represents a hydrogen atom or an alkyl group having 1 to 4 carbon atoms, R'3 represents an alkyl group having 1 to 4 carbon atoms and Hal is a halogen atom.

6. Compounds as claimed in claim 1 of the formula

in which R represents a methyl, ethyl, n-propyl or isopropyl group and Hal represents a chlorine, bromine or iodine atom.

7. The compound as claimed in claim 1 of the formula

8. The compound as claimed in claim 1 of the formula

9. The compound as claimed in claim 1 of the formula

10. The compound as claimed in claim 1 of the formula
